[57] CLAIM

The ornamental design for a purse, as shown and described.

DESCRIPTION

FIG. 1 is a front perspective view of a purse showing my new design, the broken lines for the hardware contained in the strap and closure are for illustrating environmental elements only and form no part of the claimed design;

FIG. 2 is a front elevational view thereof;

FIG. 3 is a side elevational view thereof, the opposite side elevational view being a mirror image;

FIG. 4 is a rear elevational view thereof;

FIG. 5 is a bottom plan view thereof; and,

FIG. 6 represents a cross-section view taken along lines 6—6 on FIG. 2.

The shading on the vertical hand represents an inlaid pebble-textured surface. The dotted lines shown in close proximity to the pebble-textured surface in FIGS. 1, 2, 3, 4, and 5 represent conventional stitching.
